UNITED STATES PATENT OFFICE.

THEODOR KUNDTZ, OF LAKEWOOD, OHIO.

DESIGN FOR A DRAWER FOR CABINETS.

SPECIFICATION forming part of Design No. 35,731, dated February 11, 1902.

Application filed December 17, 1901. Serial No. 86,318. Term of patent 7 years.

To all whom it may concern:

Be it known that I, THEODOR KUNDTZ, a citizen of the United States of America, residing at Lakewood, in the county of Cuyahoga and State of Ohio, have invented and produced a new and original Design for Drawers for Cabinets, of which the following is a specification, reference being had to the accompanying drawing, forming part thereof.

10 The figure is a perspective view of a drawer showing my new design.

In my design for a drawer the outer surface or front of the forward end wall *a* of the drawer is sloping. As shown, the said surface slopes forwardly and laterally outwardly, as at 5, from the inner side wall *b* of the drawer toward the outer side wall *c* of the drawer and has an outward curve or swell 6, joining the outer surfaces of the said walls *a* and *c*. A vertically-arranged molding *d* appears upon the outer surface of the forward end wall at the left-hand end of the wall and extends from top to bottom of the wall. A recess 7 in the form of a concavity is formed in the outer side of the outer side wall *c*, at the forward end of the said wall. A projection 8 appears upon the outer surface of the said outer side wall at the forward side of the recess 7 and has grooves or corrugations 25 10 diverging forwardly, and scrolls 12 appear

at the top and bottom of the said projection 8. The projection 8 extends somewhat over the forward portion of the recess 7, and a scroll 13 appears upon the outer surface of the outer side wall *c* next rearward of the recess and extends from top to bottom of the recess. 35

The leading and characteristic and essential features of the design hereinbefore described comprise the unitary design shown 40 in the illustration and consisting of the outward curve or swell 6, joining the outer surfaces of the outer side wall and the forward end wall of the drawer, the recess 7, formed in the outer side of the outer side wall at the 45 forward end of the said wall, and an ornamental projection appearing upon the said outer side wall at the forward side of the aforesaid recess.

What I claim is—

50 The design for a drawer substantially as herein shown and described.

In testimony whereof I sign the foregoing specification, in the presence of two witnesses, this 14th day of December, 1901.

THEODOR KUNDTZ.
